ASH TRAY

John R. Christian, 714-A Olive St., Yuba City, Calif.

Filed Sept. 10, 1963, Ser. No. 76,548

Term of patent 14 years

(Cl. D85—2)

FIG. 1

FIG. 2

The sides opposite those shown are substantially the same in appearance as the sides shown.

I claim:

The ornamental design for an ash tray substantially as shown and described.
